UNITED STATES PATENT OFFICE.

CHARLES L. CURTIS AND BENJAMIN ADRIANCE, OF BROOKLYN, NEW YORK.

MACHINE FOR OPENING AND FEEDING TOBACCO.

SPECIFICATION forming part of Letters Patent No. 255,494, dated March 28, 1882.

Application filed May 18, 1881. (No model.)

To all whom it may concern:

Be it known that we, CHARLES L. CURTIS and BENJAMIN ADRIANCE, of Brooklyn, in the county of Kings and State of New York, have 5 invented an Improvement in Machinery for Opening and Feeding Tobacco, of which the following is a specification.

The object of this invention is, first, to separate from a mass of tobacco so much as is required to feed a cigarette or other machine automatically and with uniformity; second, to loosen and pull apart the tobacco and render it of uniform condition as it passes from the machine.

15 In the drawings, Figure 1 is an elevation of the complete machine. Fig. 2 is a plan of the same, and Fig. 3 is a vertical section of the operative parts of the machine. Fig. 4 is a plan view of the lower feeding-belt and graduating-roller, and Fig. 5 is a plan of the cutter-bars.

25 The hopper *a* is adapted to receive the tobacco that is employed in making the cigarettes. This tobacco is generally in the form of very fine threads, and it has to be opened and separated, so as to be passed with uniformity into the machine.

At the lower part of the hopper there are 30 one or more serrated or toothed feeding rolls or cylinders, *b*, preferably formed of gangs of saws with intervening washers; and *c c* are stationary stripper-fingers, that are made of tapering curved bars that are below the toothed cylinders and occupy the spaces between the 35 saws, and act to force the tobacco off the teeth of the toothed feed-cylinders and cause it to fall in an open or loose sheet or ribbon from below the feed-rollers.

It sometimes happens that the fine threads 40 of tobacco pass in between the stripper-fingers and the saws, or they adhere to the fingers. To remove these we employ the vibrators *c'*, each of which is formed of the two end pieces having the shaft of the feed-cylinder for its 45 point of suspension, and these end pieces are united by a cross-bar, *2*, around which there are two or more volute springs, that support the vibrator-plate *c'* and press it toward the fingers *c*, and this blade serves to strip off any 50 threads of tobacco and prevent them being moved along the fingers by the action of the

saws, and to the vibrator a motion is given by a crank or arm and cam, or equivalent device, the extent of motion being indicated by dotted lines.

55 In other parts of the machine hereinafter described similar vibrators are shown, and as they all act in a similar manner to prevent the threads of tobacco accumulating upon the stripping fingers or devices, their mode of construction and operation need not be further set forth.

60 In the hopper there is a bar, *d'*, having a row of fingers or cutters on each edge, and below the same is a serrated cutter, *d*, that receives a rapid vibrating motion endwise. These fingers serve to detain the tobacco, open the same 65 as the feed-cylinders carry the tobacco down under them, and the vibrating cutter-bar, acting with the lower stationary cutter-bar, separates the tobacco and prevents the same being carried down in too great quantity by the feed-rollers. The lower cutter may be the one that is stationary, or they may both be vibrated in opposite directions. There is also a swinging 70 plate, *e'*, above the cutter-bars, that is moved first one way and then the other, as indicated by dotted lines, so as to prevent the tobacco remaining and packing into a hard mass on the cutter-bar.

75 In some cases the bar *d'*, with its fingers, may be used with the swinging plate *e'* without the vibrating cutter-bar *d*, and we remark that it is preferable to employ fingers with sharp edges that act with the vibrating cutters like shears.

80 Below the toothed feed-cylinders there is a separating-hopper, *f*, that is above the roller *g'*, and there is an opening in one side of the hopper, as at 1, through which any accumulation of tobacco will fall into a receiver, *f'*, if there is more tobacco fed down than will be supported upon the belt *g*, which passes around roller *g'*. The lower belt, *g*, passes around the small roller *5*, and there is a tightener-roller, 85 *g'*, that is acted upon by a lever or weight to keep the belt under the proper tension, and *h* is the upper belt, passing around the rollers *h'* and *6* and *7*, and *h''* is a tightener for the same, and each operative portion of the belt 90 is backed up with a table, *k* being the lower and *k'* the upper table. One or more of the

respective belt-rollers are revolved so as to move the upper and lower belt at the same speed, and the tobacco is carried along upon the lower belt, *g*, between that and the upper belt, *h*, and a layer of uniform thickness is formed, the lower edge, *f*², of the hopper *f* acting as a baffle-plate for determining the thickness of the layer that passes in upon the belt *g*.

10 There are side guides or fingers, *c*², (see Fig. 4.) that are between the two belts, and prevent the tobacco spreading widthwise of the belts.

The graduating-roller *l* is made with numerous small pins in its surface. This roller is moved at a regular speed, and serves to measure the amount of tobacco. There is a plate, *S*, that is slotted for the passage of the pins of the roller *l*, which plate extends from the belt *g* to the graduating-roller, to prevent the tobacco from lodging in the triangular space between the parts. The belts *g* and *h* are moved faster than the surface-speed of the graduating-roller *l*. Hence the tobacco is constantly pressed by the action of the belts toward the graduating-roller, the pins in which, by entering the mass of tobacco, prevent the tobacco moving faster than the graduating-roller. By the combined action of the rapid-moving belts and the retarding action of the 20 graduating-roll, the tobacco is caused to pack and fill the space between the belts. Therefore the layer of tobacco taken off by the pins of the graduating-roller will be as uniform as possible.

30 There is a toothed or serrated roll or cylinder, *m*, revolving contiguous to the graduating-roll in such a manner that the teeth of the serrated roll pass between the pins or teeth of the graduating-roll. The toothed roll *m* revolves at a much higher rate of speed than the graduating-roll, the object being the tearing or taking away of the tobacco regularly from the graduating-roll, the slow relative action of the latter aiding the result by the tobacco being held by the pins or teeth on its surface. If any tobacco escapes the action of the toothed roll, it is removed from the graduating-roll by the combined action of stripper-fingers, as *l*³, and vibrator *l*⁴, similar to those before set forth.

40 This toothed cylinder *m* is made up preferably of saws with small-sized intervening washers, and there are also intervening eccentric plates *n* between the saws, and having holes large enough for the washers between the saws.

50 These eccentric plates are kept from turning by the fixed bolt *n*², and they act to strip the tobacco from the teeth of the saws. There is also a vibrator, *l*⁴, similar to the vibrator *c*⁴, to clean the surface of eccentric strippers.

60 Power is communicated to the machine by the belt and pulley 9 upon the shaft 10, and this shaft, through various pulleys and belts, communicates motion to the other parts of the machine, as hereinafter set forth. Upon said shaft 10 there is a star cam-wheel, 11, and there is a slide, 12, one end of which slides in

a bracket upon the frame of the machine, and near the other end is an opening for the passage of the shaft 10, and this slide rests upon said shaft, or upon a friction-roller, and there are rollers 13 upon this slide 12, against which the teeth of the revolving star-cam act. The revolution of star-cam-wheel 11 gives a forward and backward movement to the slide 12, and it moves the lever 14 and swinging plate *c*¹, both of which are on the shaft 15. The slide 12 communicates a forward and backward movement to the lower or moving cutter-bar, *d*, through the L-shaped lever-arm 16, (see Fig. 2,) which is pivoted to a bracket 80 on the frame of the machine. The shafts 17 18 of the toothed feeding rolls or cylinders *b* form pivots for the lever-arms 19 20, which carry the vibrating blades *c*¹ *c*², and the upper ends of said lever-arms have slots, in which work pins upon the slide 12, and the arms 19 20 receive their swinging movement from said slide 12, and the arm 19 communicates by the link 21 motion to the lever-arm 22, that carries the vibrating blades *l*¹, and this is connected to the arm of the vibrating blade *l*¹ by the link 23. The shafts 24 and 25 of the wheel *m* and graduating-roller *l* form the pivots for the said levers.

70 The toothed feeding rollers or cylinders *b* upon shafts 17 18 are geared together on one side of the machine and driven by a pulley, 28, on the shaft 18, which is belted to a pulley, 29, on the driving-shaft 10. The roller *g*¹ is driven by a pulley, 30, on its shaft 26, which is belted to a pulley, 31, on the driving-shaft 10, and said roller *g*¹ gives motion to the belt *g*. The roller *h*¹ upon the shaft 27 is driven by a pulley, 32, and cross-belt to a pulley upon the shaft 26, and these rollers *g*¹ *h*¹ are of the same size, and the pulleys on their respective shafts are also of the same size, and the belts *g* *h* receive thereby a regular and even motion in the same direction. The graduating-roller *l* upon the shaft 25 is driven by pulley 33 upon its shaft, and a belt to a pulley, 34, upon the driving-shaft 10. The toothed roller or cylinder *m* upon the shaft 24 is driven by a pulley, 35, upon its shaft, which is belted to a pulley, 36, on shaft 26. (See Fig. 2.)

80 We would here remark that the sizes of the various pulleys on the driving-shaft and the sizes of the pulleys on the operating-shafts are so graded and the speed of the parts so timed thereby that the best practically operative results are obtained; but we do not limit ourselves to the sizes of these pulleys or to the relative speeds of the operating mechanism, as these may be changed without departing from the essential features of invention.

90 The devices thus far described are specially intended for use in preparing the tobacco for cigarettes; but it will be obvious that the above-described feeding device can be used in any machine where an automatic tobacco-feed is required, either in the combination of the hopper-feed and graduating belts and roll, or

separately, the hopper-feed alone being sufficient where perfect uniformity of feed is not essential.

There are three several ways in which we 5 may use the feeding device:

First, we may use it in the combination and manner fully described and set forth.

Second, we may remove the hopper-feed and substitute hand or other feed in its stead, the 10 combination of the graduating belts and rolls remaining as set forth, the lower belt being extended so as to receive the tobacco upon it; or,

Third, we may extend the lower belt to any 15 convenient length, move it and the upper belt 15 at the same speed, and both at the speed of the graduating-roll. In this case we would substitute for the hand or hopper feed the distribution of a fixed weighed quantity of tobacco evenly distributed over a fixed or determined 20 superficial area of belt, all so proportioned as to supply the proper amount of tobacco.

We claim as our invention—

1. The combination of a feed-hopper, one or 25 more toothed feed-cylinders, stripper-fingers, and vibrators, substantially as set forth.

2. The combination, with the hopper and toothed feed-rollers, of the stationary cutter-fingers and reciprocating cutter-bar, substantially 30 as set forth.

3. The combination, with the hopper, feeding-cylinders, and stationary and vibrating cutters, of the swinging plate e' , substantially as set forth.

35 4. The combination, with the hopper and toothed feeding-cylinder, of the fingers d and swinging plate e' , substantially as set forth.

5. The combination, in a tobacco-feeding ma-

chine, of the hopper, toothed feed-rollers, separating-hopper f , with a mouth at one side, and 40 the roller or belt g , substantially as set forth.

6. An endless belt, g , in combination with the graduating-roller l , having pins upon its periphery, substantially as set forth.

7. The endless belts g and h and their respective rollers and belt-tables, in combination 45 with the graduating-roller l , having pins or teeth on its surface, substantially as set forth.

8. The endless belts g and h and their respective rollers and belt-tables, in combination 50 with the graduating-roller l , having pins or teeth on its surface, and the guide-fingers between the belts, substantially as set forth.

9. The combination, with the belts g and h , of the graduating-roller l , having pins or teeth 55 in its surface, and the notched bridge 8 between the belt g and the graduating-roller l , substantially as set forth.

10. The combination, with the belts g and h and baffle-plate f^2 , of the graduating-roller 60 having pins or teeth in its surface, substantially as set forth.

11. The combination, with the belts g and h and graduating-roller, of the strippers b^3 and vibrator b^4 , substantially as set forth. 65

12. The combination, with the graduating-roller, of the serrated or toothed cylinder m and eccentric strippers and vibrator, substantially as set forth.

Signed by us this 13th day of May, A. D. 70
1881.
